W. C. WALLIS

WRENCH

Filed Feb. 16, 1926

WITNESS:

Frank J. Evans

BY *Victor J. Evans*

ATTORNEY

UNITED STATES PATENT OFFICE.

WALTER C. WALLIS, OF CLOVIS, NEW MEXICO.

WRENCH.

Application filed February 16, 1926. Serial No. 88621.

This invention relates to improvements in wrenches, and especially to that form of wrench commonly known as the open end type, and which contemplates the provision 5 of companion halves, pivotally associated adjacent one pair of jaw faces while the opposite end having adjusting means interposed therebetween whereby the adjustment upon one set or pair of jaw faces will simultaneously set the faces upon the opposite end.

Another object of my invention resides in the provision of the adjusting means constituting a pair of threaded shanks received within aligned openings arranged in the opposite 15 sides of the members composing the wrench, the intermeeting ends of the shanks provide a universal joint of association and include a relatively enlarged knurled portion at this juncture whereby the shanks will 20 not bind within the members incident to the adjustment of the wrench.

With the above and other objects in view, the invention further includes the following novel features and details of construction, 25 to be hereinafter more fully described, illustrated in the accompanying drawings and pointed out in the appended claims.

In the drawing:—

Figure 1 is an elevation partly in section, 30 of my wrench.

Figure 2 is a section taken on line 2—2 of Figure 1.

Figure 3 is a vertical sectional view taken on line 3—3 of Figure 2.

Figure 4 is a fragmentary end elevation 35 of a modified form of my invention.

Figure 5 is a perspective of a swivel forming the subject matter of the modified form of my invention.

Referring to the drawing in detail, wherein like characters of reference denote corre- 40

sponding parts, the reference characters 10 and 11 indicate companion handle members respectively: each of which having enlarged

45 portions 12 adjacent one end for the reception of a pivot pin 13 therethrough whereby the jaw faces 14 may be readily swung to open and closed positions. The opposite ends of the companion handles 10 and 11 have

50 larger jaw faces or jaws 15, one of which provides a cutout portion 16 upon its innerside, the purpose of which will be presently apparent.

In order to provide means to facilitate relative adjustment of the respective jaws 14 and

15 respectively: I provide shanks 17 and 18 having right and left hand threads thereon and imbedded or threaded within transversely disposed openings provided upon the innersides of the jaws 15. The shank 18 has a 60 relatively enlarged knurled portion 19 upon its inner end which provides a socket 20 therein for the reception of the inner end of the shank 17 in order that a pivot pin 21 may be positioned within the socket whereby a pivot 65 or universal joint is provided at this juncture and which obviates any possibility of the respective shanks 17 and 18 from becoming jammed or distorted within the transversely disposed openings provided in the opposite 70 and innersides of the jaw faces 15 while relatively adjusting the same.

As clearly illustrated in Figure 1 of the drawing the knurled portion 19 formed integrally upon the inner end of the shank 18 is 75 positioned and adapted for rotation in either direction within the cutout portion 16 provided upon the innerside of the relatively enlarged jaw provided upon the corresponding end of the handle member 11. 80

In Figures 4 and 5 of the drawing, I have illustrated a modified form of my invention, the main characteristic, differences, and departure constituting the subject matter there- 85 of being the provision of a locking or securing means for the adjusting shank to be presently described as follows:

As clearly illustrated in Figure 4 of the drawing the handle members 10' and 11' respectively have jaw faces 12' upon their outer 90 ends, the jaw faces upon the outer end of the handle member 11' includes a cutout portion 13' similar in construction and capable of being used in a like manner to that of the cutout portion 16 of the preferred form of my 95 invention.

Each of the jaw faces or jaws 12' have elongated slotted portions 14' therein and registering with threaded openings extending transversely through the handle members 10' and 11' and the respective jaws 12' there- 100 for whereby the oppositely threaded shanks 15' extending in opposite directions from an enlarged knurled portion 16' formed integral- 105 ly therewith and at the junctures of their inner ends is positioned within cutout portion 13' as illustrated.

Positioned within the vertically disposed elongated slotted portions 14' are nuts for 110 swivels 17' having threaded openings 18' pro-

vided centrally thereof for the reception of the opposite and outer ends of the shanks 15' and owing to their looseness, that is, the side and end play incident to the positioning thereof will obviate any apparent binding of the shanks 15' when the jaws 12' are moved to extreme open and closed positions.

- It will thus be noted from the foregoing description and accompanying drawing that 10 a novel form of adjustable open end wrench is defined, capable of functioning in the manner as described and owing to the construction thereof may be made in various sizes to correspond with its work and prove of great 15 value to machinists and mechanics in so far as a whole set of different sized open end wrenches may not be required to complete an outfit of tools and consequently cheaper for maintenance.
- 20 The invention is susceptible of various changes in its form, proportions and minor details of construction, and the right is herein reserved to make such changes as properly fall within the scope of the appended claim.

Having thus described my invention what 25 is claimed is:—

A wrench comprising pivotally connected handle members provided with oppositely disposed jaw faces, one of said handle members being provided with a cut-out portion adjacent the jaw face therefor, shanks threaded within the handle members, an enlarged elongated portion carried upon the inner end of one of the shanks and disposed within the cut-out portion of the particular handle member, said portion being provided with a socket opening within the free end thereof and including beveled peripheral edges communicating therewith, the adjacent end of the remaining shank reposing within said socket, 40 and a pivot pin passing through said end and the opposed side walls of the enlarged portion to permit relative adjustment to the handle members and to relieve binding action at the juncture of association of the respective 45 shanks.

In testimony whereof I affix my signature.
WALTER C. WALLIS.
